GUSTAVE HOFMANN INVENTOR.

BY

Richard B. Duren
ATTORNEY.

UNITED STATES PATENT OFFICE.

GUSTAV HOFMANN, OF BELGRADE, MINNESOTA.

RADIATOR.

Application filed April 23, 1921. Serial No. 463,742.

To all whom it may concern:

Be it known that I, GUSTAV HOFMANN, citizen of the United States, residing at Belgrade, in the county of Stearns and State 5 of Minnesota, have invented certain new and useful Improvements in Radiators, of which the following is a specification.

This invention relates to radiators and has for its principal object to generally 10 prove upon radiators which are used in connection with internal combustion engines for cooling purposes by providing a device which will be of extremely simple, durable and inexpensive construction, one which is 15 efficient and reliable in operation, and well adapted to the purpose for which it is designed.

Another object of the invention is to provide a partition arranged in a zigzag manner so as to form a plurality of cooling 20 chambers having tubes passing therethrough.

With these and numerous other objects in view, the invention resides in certain 25 novel features of construction, and the combination and arrangement of parts as will be hereinafter fully described and claimed.

In the drawing:—

Figure 1 is a front elevation of the radiator showing a portion of the forward wall 30 broken away,

Figure 2 is a transverse sectional view taken on the line 2—2 of Figure 1 looking in the direction of the arrow, and

Figure 3 is a fragmentary enlarged 35 sectional view taken through the radiator showing one of the tubes in section.

Referring to the drawing in detail it will be seen that 1 designates the cooling chamber of the radiator which is formed by the 40 front and rear walls 2 and side walls 3 and is substantially rectangular in transverse cross section as shown in Figure 2. A zigzag partition 4 is arranged in the cooling chamber 1 so as to form the triangularly 45 shaped compartments 5. This zigzag partition 4 efficiently braces the casing formed by the walls 1 and 2 so as to present a radiator of comparatively very rigid construction.

A plurality of tubes 6 pass through each of the compartments 5 and are arranged so 50 as to pass through the apexes thereof as is shown to advantage in Figure 2. Each tube 6 is provided with flared ends registering with suitable openings in the front and rear walls 2. The top wall 7 of the cooling 55 chamber 1 is provided with a plurality of apertures so that the various compartments 5 will be in communication with the reservoir 8 to which is delivered the hot water from the internal combustion engine in the 60 usual manner. The compartments 5 will be in communication with each other in the lower portions of the partition 4.

From the foregoing description, taken in connection with the accompanying drawing, 65 the construction and operation of the radiator will be readily understood without a more extended explanation. As numerous changes in form, proportion, and in the minor details of construction may be resorted to without departing from the spirit 70 of this invention, I do not wish to be limited to the construction herein shown and described other than as claimed.

Having thus described my invention what I claim as new is:—

A radiator comprising a cooling chamber, a reservoir in communication therewith, a zigzag partition arranged in the chamber so as to form a plurality of substantially triangular shaped compartments, said partition provided with apertures in its lower portion so that said compartments will be in communication with each other, and a plurality of tubes passing through said compartments and arranged in series so as to 85 pass through the apexes of the compartments, each tube provided with flared end portions.

In testimony whereof I affix my signature in presence of two witnesses:

GUSTAV HOFMANN.
